UNITED STATES PATENT OFFICE.

FREDERICK A. STAFFORD, OF CHARITON, IOWA.

SILO STRUCTURE.

1,381,894.

Specification of Letters Patent. Patented June 14, 1921.

Application filed March 18, 1919. Serial No. 283,410.

To all whom it may concern:

Be it known that I, FREDERICK A. STAFFORD, a citizen of the United States, and resident of Chariton, in the county of Lucas and State of Iowa, have invented a certain new and useful Silo Structure, of which the following is a specification.

The object of my invention is to provide a silo structure of extremely simple and 10 relatively inexpensive construction.

More particularly it is my object to provide a structure comprising a receiving member, such, for instance, as a silo, having preferably a series of vertically spaced 15 door openings, and to provide in connection with said openings door members which in each case consist of a single piece of sheet metal bent to conform in curvature to the circumferential curvature of the silo, 20 which sheet metal door members are provided with transverse angle iron braces on their outer surfaces adapted to brace the door members and also to serve as means for properly spacing the door members in 25 the door openings.

Still a further object is to provide in connection with such a structure a simple means for locking the door sections in position temporarily or for a longer time, if desired.

30 With these and other objects in view, my invention consists in the construction, arrangement and combination of the various parts of the device, whereby the objects contemplated are attained, as hereinafter more 35 fully set forth, pointed out in my claim, and illustrated in the accompanying drawings, in which:

Figure 1 shows a front elevation of a silo structure embodying my invention.

40 Fig. 2 shows a vertical sectional view taken on the line 2—2 of Fig. 1.

Fig. 3 shows a front elevation of one of the door sections.

Fig. 4 shows a horizontal sectional view 45 taken on the line 4—4 of Fig. 1; and

Fig. 5 shows a vertical, sectional view of a door section, the fastening and reinforcing devices therefor being shown in side elevation.

50 In the accompanying drawings I have used the reference numeral 10 to indicate generally a circular structure having the form of a silo. The silo 10 is provided with a vertically spaced series of door openings 11.

For closing the different door openings I

have provided in each case a door comprising a sheet metal door member 12. The door members 12 are curved from side to side, as illustrated in Figs. 2 and 4, to conform to the curvature of the interior of the silo wall and to enable the door sections to fit snugly against the interior of the wall. The door members 12 are of such height and width as to overlap the door openings 11, as 60 clearly illustrated in Figs. 2 and 4, both on the sides and at the top and bottom of such openings.

On the outer surface of each door member 12 are secured transverse angle iron 70 brace members 13, 14 and 15, preferably three in number. The lower brace member has one flange extending upwardly and secured to the door member 12, and has its lower flange extending from the lower edge 75 of the upper flange outwardly, as shown in Figs. 2 and 3. The upper angle iron 15 has its horizontal flange at the top of the angle iron, as illustrated in Fig. 2.

The lower angle iron 13 is so located with 80 relation to the general outline of the door member 12 as to form a means for supporting the door member 12 within the opening 11, as shown, for instance, in Fig. 2.

The brace members 13, 14 and 15 terminate short of the side edges of the door member 12, so that the said brace members may project into the opening 11. They also serve to limit any sidewise movement of the door member when such door member 90 is installed, and thus assist in properly holding the door member within the opening 11.

Secured to the outwardly extending flange of the middle brace 14 is a bracket or the like 95 16, in which is mounted a bolt 17.

For fastening the door members 12 in position where it is desired to lock them securely, I provide a transverse bar 18 which fits against the silo wall adjacent to the 100 sides of the opening 11, as illustrated in Fig. 4. The bolt 17 extends through the bar 18 and has on its outer end an adjustable nut 19, whereby the door member 12 may be tightly drawn against the interior of the silo 105 wall.

As a matter of fact, in filling the silo with ensilage I preferably use the bars 18 during the filling process, but after the ensilage has been put into the silo and the silo 110 is filled to a point above any door member, then the bar 18 of that door member may be

removed, if desired, and the ensilage will hold the door properly in place. The lower flange of the brace 14 will prevent the door from settling downwardly and leaving a 5 crack at the top of the door opening, and the braces prevent any sidewise movement of the door.

The door being made of sheet metal is so thin that when the ensilage settles the door 10 members do not interfere with such settling and no open spaces are left in the ensilage, and I find that with a door of the type herein set forth there is less spoiling of the ensilage than with any other door with 15 which I am familiar.

It will be seen that my entire structure is of extremely simple construction. By using 20 doors of this type instead of the ordinary doors, which are more expensive to make, and which require the providing of rabbets 25 around the interior of the door openings, I am able to very substantially reduce the expense of building a silo and equipping it with doors, and I find that it is easier to maintain tight joints with a very simple 30 door of the kind mentioned and described than with other more expensive and more complicated doors.

It will be noted that there is a portion 35 of the door member 12 outside the outlines of the cross braces thereon, which portion is not braced and can bend slightly so as to fit snugly to the interior of the silo wall.

In this connection it may be mentioned 40 that these door members have a certain amount of resiliency which enables them to be sprung by the weight of the ensilage on the interior of the silo, so as to properly fit around the door opening in case of any slight inequalities or uneven places in the silo wall.

As the ensilage is removed the doors can be removed without any difficulty whatever, and stored in any ordinary way.

45 Most farmers plaster a little mud or clay in the rabbet around the door so as to make an air tight seal around the door. Since it freezes some in all silos in this country it is easy to take a silage fork and slide it down 50 between the door and silo with my structure, which would be impossible if there were a rabbet for the door to set in.

No special tool or work is necessary for

removing a door of this kind, and it is not necessary to dig around the edge of the 55 door in any rabbet or groove in the silo wall in order to remove the silo door after the ensilage adjacent thereto has been taken out of the silo.

The means for locking the door in position is obviously extremely simple and yet is readily adjustable.

It will be noted that doors of this kind may be made in standard sizes and may then be fitted to any sort of silo wall, whether 65 monolithic concrete, concrete blocks, tile, brick or wood. It is further obvious that on account of the means whereby the door is locked in position, doors of standard sizes may be used for silo walls of greatly varying 70 thicknesses.

Some changes may be made in the construction and arrangement of the parts of my improved device without departing from the essential spirit thereof, and it is my 75 object to cover by my claim any modified forms of structure or use of mechanical equivalents which may be reasonably included within its scope.

I claim as my invention:

In a device of the class described, the combination of a circular structure having a door opening therein, a door member for said opening comprising a sheet of somewhat resilient metal curved from side to side to conform to the curvature of the structure and overlapping the wall of the structure at the sides and top and bottom of the opening, transverse brace members on the outer surface of said door member near the top and bottom thereof, terminating short of the side edges of said door member, and adapted to engage the wall of the opening for properly positioning the door member with relation to said opening, a central, transverse, reinforcing angle member on the outer surface of said door member, a second angle member secured to said first angle member, a cross bar designed to overlap the door opening on the opposite side thereof from the door member, a bolt mounted in said second angle member extending through said cross bar, and a nut for said bolt.

Des Moines, Iowa, February 13, 1919.

FREDERICK A. STAFFORD.
